UNITED STATES PATENT OFFICE

2,286,491

REFRIGERATING APPARATUS

Andrew A. Kucher, Dayton, Ohio, assignor to
 General Motors Corporation, Dayton, Ohio, a
 corporation of Delaware

Application March 30, 1940, Serial No. 326,853

4 Claims. (Cl. 183—32)

This invention relates to refrigerating apparatus and more particularly to refrigerating apparatus for use in air conditioning.

One object of this invention is to provide a simplified inexpensive air conditioning unit which may be conveniently mounted either in a small cabinet or directly in a duct system.

Another object of this invention is to improve the general arrangement of the elements so as to facilitate service and repair of the parts without increasing the cost of production.

A further object of this invention is to improve the air flow through the conditioning cabinet.

Still another object of this invention is to improve upon the hermetically-sealed refrigerating system so as to improve the operating efficiency of the refrigerating system.

In the usual air conditioning installation in which a portable type of unit is desired, it is as a general rule necessary to provide an outer cabinet for enclosing the apparatus. In order to make full use of this cabinet, it is an object of this invention to utilize this cabinet not only as a part of the air duct system but also as a means for more conveniently supporting the air conditioning apparatus.

A still further object of this invention is to so arrange the elements within the air conditioning cabinet that the hermetically-sealed volatile refrigerating system may be readily removed from the cabinet as a unit without disturbing the air circulating means, the air filter, and the air grilles.

Further objects and advantages of the present invention will be apparent from the following description, reference being had to the accompanying drawings, wherein a preferred form of the present invention is clearly shown.

In the drawings:

Fig. 1 is an elevational view with parts broken away showing a preferred embodiment of my invention;

Fig. 2 is a vertical sectional view taken on line 2—2 of Fig. 1;

Fig. 3 is a perspective view of the cabinet with the refrigerating apparatus removed;

Fig. 4 is a perspective view of the refrigerating apparatus which is removable from the cabinet as a unit;

Fig. 5 is an elevational view with parts broken away showing one application of the apparatus disclosed in Fig. 4; and

Fig. 6 is a diagrammatic view partly in section showing the controls used for the refrigerating apparatus.

In the preferred embodiment of my invention, the air conditioning cabinet generally designated by the reference character 10 comprises a lower section 12 and an upper section 16. The lower section 12 is of sufficiently rigid construction to support the apparatus therein without the use of a separate angle iron frame.

The upper section 16 constitutes a plenum chamber removably mounted on the upper end of the lower section 12. As best shown in Fig. 3, the lower section 12 is provided with a hinged door 18 which has incorporated therein an air inlet opening 20 provided with louvers 21 and a pair of replaceable filter elements 22 which are slidably supported by means of the guides 24 and 26 whereby the filter elements may be removed by sliding the filter element upwardly in the guides.

As shown in Fig. 2 the louvers 21 are arranged so as to draw air to be conditioned from the lower portion of the air conditioned space. The opening 20 is sufficiently high to prevent floor dust and the like from being picked up by the return air stream. Track elements 28, which may be welded or otherwise secured directly to the side walls of the cabinet 12, are adapted to removably support the entire volatile refrigerant system comprising the evaporator 30, the hermetically-sealed motor-compressor-condenser-receiver unit 32, the switch box 34 and all of the refrigerant flow connections between the hermetically-sealed unit 32 and the evaporator 30.

As best shown in Figs. 1 and 4, the hermetically-sealed motor-compressor-condenser-receiver unit 32 is supported from a main frame 36 by means of resilient mounting brackets 38. The resilient mounting bracket 38 includes a pair of rubber-like mounts 40 which absorb any vibration which may be produced by the rotating parts of the motor-compressor mechanism. The main frame 36 is provided with rollers 42 which facilitate removal of the frame 36 from the supporting brackets 28.

The evaporator 30 is provided with a condensate drain pan 44 which is provided with a drain connection 46 through which the condensate is discharged to waste. The end plates 48 of the evaporator are constructed (as best shown in Figs. 2 and 3) so as to be in engagement with the air directing baffles 50 and 52 carried by the casing 12. By virtue of this arrangement all of the air entering the cabinet through the return air opening 20 or the fresh air duct 54 must pass over the evaporator before being picked up by the blower element 56 which discharges the con-

ditioned air upwardly through a steam or other type of reheat coil 58 located in the plenum chamber 16. The air entering the plenum chamber 16 from the fan unit 56 is discharged through the air outlet grille 60 provided in the front wall of the plenum chamber 16. The outlet air grille 60 comprises a plurality of horizontally disposed and individually adjustable air directing vanes 62 and a plurality of vertically disposed independently adjustable air directing vanes 64 arranged directly behind the horizontal vanes 62. The blower unit 56 is of the centrifugal type and is driven by means of an electric motor 57. The blower 56 and the blower operating motor 57 are both mounted on a common frame 68 which is resiliently supported by means of resilient mounts 69 on the cross bars 70 carried by the main casing 12. The reheat coil 58 is supported on the frame 72 which is secured to the upper end of the casing 12.

As clearly shown in Fig. 4, air entering the lower portion of the cabinet 12 is free to flow from the space occupied by the motor-compressor-condenser into the space occupied by the evaporator since the cabinet has not been divided into compartments. By virtue of this arrangement, the fresh air duct 54 may be arranged to introduce fresh air through the back wall of the cabinet into the lower portion of the casing 12 from whence the fresh air may flow upwardly into the space in front of the evaporator.

All of the walls of the cabinet sections 12 and 16 are lined with insulating material 74 which not only serves to deaden the noises but also serves to insulate the outer walls of the cabinet so as to prevent the outer walls from becoming cold enough to serve as a condensing surface for the moisture in the room air.

In referring to Fig. 2, it will be noted that a sheet metal inner liner 76 has been provided at the rear of the evaporator chamber. The lower edge of the inner liner 76 terminates directly above the condensate drain pan 44 and is provided with an inwardly projecting lip 78 which terminates in close proximity to the baffle 80 secured to the bottom wall of the condensate drain pan 44. By virtue of this arrangement the air flowing over the evaporator is prevented from interfering with the proper drainage of the condensate which might collect on the wall 76.

The motor-compressor-condenser unit comprises a conventional rotary compressor unit 81 supported from the main frame 82 of the hermetically-sealed unit 32. The drive shaft 84 of the compressor is journaled in the main bearing 86 formed integral with the main frame 82. Secured to the upper end of the main drive shaft 84 is a conventional motor rotor 88. A cylindrical motor stator support 90 which supports a conventional motor stator 92 is also formed integral with the frame 82. In the lowermost portion of the hermetically-sealed unit 32 there is provided a supply of lubricant 94 which may be used for lubricating the bearing surfaces of the motor-compressor unit in any well-known manner. The refrigerant vapor returning from the evaporator 30 enters the compressor at 96. The compressed refrigerant discharges through the discharge passage 98 provided in the main frame 82. The compressed refrigerant vapor passes upwardly between the motor rotor and the motor stator into the upper portion of the main dome 100 which cooperates with the frame element 82 to form a condensing cavity. In order

to remove the heat of condensation, a cooling fluid such as water is supplied through pipe 102 and flows through a coil 104 arranged in the space between the cylindrical motor stator support 90 and the outer dome 100. The cooling fluid leaves the unit through the line 106. The quantity of cooling water flowing through the coil 104 is controlled by a conventional pressure responsive valve 108 which responds to the high side pressure within the main condensing chamber. In order that the valve 108 may respond to the condensing pressure, a line 110 is provided between the pressure chamber of the valve 108 and the interior of the main condensing chamber. The condensed refrigerant collects in the lower portion of the space between the wall 90 and the outer dome 100 and flows to the evaporator 30 through the liquid line 112 which supplies liquid refrigerant to the manifold 114.

As diagrammatically shown in Fig. 6, the evaporator is provided with a plurality of independent passes 116, 117, 118, 119 and 120. The flow of refrigerant to each pass of the evaporator is controlled by a separate restrictor 122 of the capillary tube type. By properly designing the size and length of the restrictor tubes the amount of refrigerant supplied to each pass of the evaporator may be so controlled as to control the temperature distribution on the evaporator. In the system disclosed herein, the passes have been shown arranged in parallel with respect to the air flow. Inasmuch as the amount of air flowing over some of the passes is greater than over other of the passes in the system shown herein, it is possible to compensate for the uneven air flow by properly designing the restrictors.

It is within the purview of this invention, however, to arrange the passes of the evaporator so that the air flows over the passes in series rather than in parallel. As pointed out hereinabove, by properly designing the restrictor tubes, a different amount of refrigerant may be supplied to each pass of the evaporator. Thus, with the passes of the evaporator arranged so as to cause the air to flow over the passes in series, the amount of refrigerant supplied to each pass may be so adjusted as to cause each succeeding pass of the evaporator to be cooler.

The compressor motor may be started and stopped in response to the return air temperature by providing a switch 124 in the motor circuit operated by a conventional thermostatic bulb arrangement 126, which for purposes of illustration has been shown placed in the return air stream. A manual switch 128 is provided which makes it possible to turn off the compressor motor without turning off the blower motor 57. A separate manual switch 130 is provided which makes it possible to completely shut down the entire apparatus.

While I have shown a conventional dry bulb control, it is within the purview of this invention to use other types of controls such as wet bulb, combinations of wet and dry bulb or effective temperature controls. The controls may be placed so as to be responsive either to the room air, the outside air or a combination of both.

While I have shown the air outlet grilles mounted in the front wall of the plenum chamber, I have also provided an opening 150 in each of the side walls of the upper section 16 of the cabinet as shown in Fig. 3 into which an air grille may be mounted. The size of the opening 150 is equal to half the size of the entire air

outlet opening in the front side of the plenum chamber. The air grille 68 is made up in two sections, any one of which may be transferred to a side opening 150. As shown in Fig. 3, the side opening 150 is provided with a closure member 152 which is adapted to close the opening not being used. No filter has been provided at the air outlet as the return air passes through the filters 22 provided adjacent the return air inlets and the fresh air passes through a filter 154 provided in the fresh air duct 54.

In Fig. 5 I have shown a slightly modified arrangement in which the refrigerating unit disclosed in Fig. 4 is used in combination with a horizontally disposed air flow passage 140. The refrigerating system shown in Fig. 5 is identical to the refrigerating apparatus disclosed in Fig. 4. In this modified arrangement the refrigerating apparatus is inserted in place through an opening in the lower wall of the duct 140. The refrigerating apparatus is supported in place by means of bolts 142 or any other suitable means of support. The lower portion of the apparatus may be enclosed within a cabinet 144 provided with an access door 146.

While the form of embodiment of the invention as herein disclosed, constitutes a preferred form, it is to be understood that other forms might be adopted, all coming within the scope of the claims which follow.

What is claimed is as follows:

1. In a portable air conditioning apparatus; a casing; air circulating means arranged within the upper portion of said casing; and a complete self-contained volatile refrigerant system removably supported within the lower portion of said casing and comprising in combination, a frame member slidably supported within said casing, an evaporator carried by said frame member and disposed beneath said air circulating means, a hermetically-sealed rotary motor-compressor-condenser unit in refrigerant flow relationship with said evaporator carried by said frame member and disposed beneath said evaporator, means for flowing air to be conditioned into the space surrounding said hermetically-sealed motor-compressor-condenser unit and then into thermal exchange relation-

ship with said evaporator before discharging into the space to be conditioned.

2. In a portable air conditioning unit, a cabinet forming an air flow passage, a self-contained volatile refrigerant system removably supported within said cabinet directly in the air flow passage, a blower and blower motor permanently mounted within said cabinet, an opening in one wall of said cabinet through which said volatile refrigerant system may be inserted into said cabinet and withdrawn from said cabinet as a self-contained unit, a closure member for said opening, and removable filter elements carried by said closure member.

3. In a self-contained air conditioning unit, a casing, a blower and blower motor resiliently supported directly by said casing, a rack member in said casing removably supported by the walls of said casing, an evaporator supported on the upper side of said rack member, a motor-compressor-condenser means supported from the lower side of said rack member, means for introducing fresh air to be conditioned into the space surrounding said motor-compressor-condenser means, means for introducing recirculated air into said cabinet, and means whereby a mixture of fresh air and recirculated air flows in thermal exchange relationship with said evaporator and is thereafter discharged through an air outlet in the upper portion of said cabinet.

4. A self contained air conditioner comprising in combination, a cabinet, an evaporator in said cabinet, a sealed motor-compressor-condenser unit in said cabinet, means for flowing a stream of air to be conditioned in thermal exchange with said evaporator, refrigerant flow connections between said evaporator and said sealed motor-compressor-condenser unit, said sealed motor-compressor-condenser unit comprising a sealed casing enclosing the motor and the compressor and into which the compressed refrigerant is discharged and a water coil located adjacent the outer wall of said sealed casing for removing the heat dissipated by said sealed motor-compressor-condenser unit, said sealed casing being arranged directly in said air stream.

ANDREW A. KUCHER.
